DESIGN FOR A FENCING IMPLEMENT FOR PRACTICE IN FENCING

Peter Jensen, New York, N. Y.

Application July 14, 1938, Serial No. 78,474

Term of patent 7 years

To all whom it may concern:

Be it known that I, Peter Jensen, a subject of the King of Denmark, residing at New York city, county and State of New York, have invented a new, original, and ornamental Design for Fencing Implements for Practice in Fencing, of which the following is a specification, reference being had to the accompanying drawing, forming part thereof, and in which:

Figure 1 is a front elevational view of a fencing implement showing my new design.

Figure 2 is a side elevational view of the same.

I claim:

The ornamental design for a fencing implement for practice in fencing, as shown.

PETER JENSEN.
